KNITTING MACHINE

Thomas S. Hayhurst, Belle Harbor, N. Y., assignor
to Max Nydegger, Summit, N. J.

Application April 13, 1944, Serial No. 530,767

8 Claims. (Cl. 66—63)

The present invention relates to an improvement in knitting machines. An object thereof has been to provide improved mechanism by which to selectively position devices such as a selector bar for actuating control jacks in knitting machines more particularly of the links or knit purl type, whereby predetermined ones of said devices may be selected to operate predetermined control jacks or sets thereof.

One embodiment of my invention in a form adapted for use with an automatic multiple flat links knitting machine is described in the following specification and illustrated in the drawings appended thereto and in which—

Figure 1 is a view partly in plan and partly in horizontal section of a right end portion of a full automatic links-links knitting machine incorporating the improved selector bar actuating mechanism;

Figure 2, a view in front elevation and with parts broken away of a portion of the end of the machine illustrated in Figure 1;

Figure 3, a fragmentary view on the line 3—3 of Figure 1, showing the control link which operates with another similar link, as seen in Figure 3, in the automatic control of selector bar positioning devices;

Figure 4, an enlarged fragmentary horizontal section on the line 4—4 of Figure 2 showing a portion of the profile bar and lifter plate (jacquard) selecting or conditioning mechanism;

Figure 5, a transverse vertical section on the line 5—5 of Figure 4;

Figure 6, a transverse vertical section on the line 6—6 of Figure 4;

Figure 7, a transverse vertical section, enlarged, on the line 7—7 of Figure 1;

Figure 8, a portion of Figure 7 further enlarged to more clearly show parts of needle jack conditioning devices;

Figure 9, a view partly in horizontal vertical section on the line 9—9 of Figure 8 and with portions broken away and with some parts removed.

Figure 10, a simplified section illustrating the relative positions of the parts when the locking bar is in intermediate or change position and the main jacks are free to be moved upwardly, the selector bar being shown in raised position to engage and lift a profile bar;

Figure 11, a fragmentary view of parts as shown in Figure 10 and with a lift plate raised to an intermediate main jack lifting position by the selector bar;

Figure 12, a view similar to Figure 11 with the

lift plate raised to a higher main jack lifting position;

Figure 13, a view in elevation of a typical profile or jacquard bar forming part of the needle jack conditioning mechanism;

Figure 14, a fragmentary view in elevation of a group of three different profile bars, with outer portions broken away, to illustrate the relative positions of the dependent lugs on said several bars; and

Figure 15, an enlarged fragmentary transverse vertical section illustrating portions of the front and rear needle beds, a needle, and jacks operatively related thereto and to the knitting cams.

15 In the knitting machine shown in the drawings, the needles 23, Figure 15, are positioned or conditioned to produce predetermined pattern effects by appropriate operation of the needle jacks, as 28, Figure 8, which are moved inwardly to different operative positions in relation to the knitting cams 34, 35 by push jacks 193 actuated by push-in bar 195. A set of control jacks is used in conjunction with other devices to determine the operative effect on each said needle jack and needle of each corresponding push jack 193.

Such a set of control jacks includes, Figure 8, said push jack 193, the connecting jack 294, main jack 293, interposed jack 295, and cross jack 291. Connecting jack 294 engages an under portion of push jack 193 and is vertically adjustable to vary the angular position of said push jack 193 and thus to determine whether the latter, when moved inwardly, shall cause its corresponding needle to remain idle, to knit links-links, or to knit straight.

30 35 40 45 50 55 60 65 70 75 80 85 90 95 100 Unless idled, as by operation of cross jack 291 and interposed jack 295, or otherwise, the connecting jack 294 is raised, when locking bar 285 is in change position, Figures 10, 11, 12, by lifting main jack 293 to one or another of two positions to produce either links-links or straight knitting. This is effected by various means for different purposes: as by the gathering bar 321, to position all active needles to knit alike, i. e. all links-links or all straight; by lifter plates 345, 346, Figures 9, 11, 12, to condition predetermined end needles for decking, in which case said end needles are positioned as for straight knitting, or to condition said end needles for links-links; and by profile bars 277, 277a and 277b, Figures 10, 13 and 14, to differentially and selectively position the active needles, some for links-links and some straight, to produce different pattern characteristics in the same course of the knitted product.

Said gathering bar 321 is lifted by operation of push rod 330 and parts connected thereto.

Said lifting plates 345, 346 are actuated to raise main jacks 293 by raising fashioning bar 341 against an under surface thereof. This in turn is effected by raising the selector or slide bar 502 to bring the lift lugs 281 thereon against one or the other of the sets of depending short lugs 343, or long lugs 344, on fashioning bar 341, Figures 11 and 12.

The profile bars 277, 277a, 277b, etc., are provided in sets having different pattern producing characteristics, as the three bars shown, Figure 14. Each bar 277 has spaced depending lugs 280; and the lugs 280a, 280b of each of said other bars are differently positioned longitudinally in relation thereto from the lugs of each other bar. Said differential positioning corresponds in extent to the space between each short lug 343 and its adjacent long lug 344 on fashioning bar 341. Said bars 277 are actuated to raise main jacks 293 by raising selector bar 502 from normal position (dotted line Figure 10) to bring said lift lugs 281 thereon into engagement with the depending lugs 280 of one or another of said sets of bars 277.

Selector bar 502 is raised to lift said fashioning bar 341 and thereby said lifting plates 345, 346 and to raise said profile bars 277 through lift lugs 281 by push rod 509 and suitable devices connected therewith.

Selector bar

Means have been described above whereby the main-jack lifting instrumentalities, as the profile bars 277, the fashioning bar 341 and thereby the lifting plates 345 and 346, are raised to effect the operation of predetermined selected needle jacks 28 and their needles through corresponding sets of control jacks.

Means are also provided for determining which ones of said profile bars shall be lifted and to what level said lifting plates shall be raised while the latter are in any position of adjustment to actuate one or more predetermined or selected main jacks. One embodiment of such means and of parts operatively related thereto is herein-after described and illustrates the subject matter of the appended claims.

As seen in Figure 9, the profile and fashioning bar lift lugs 281 are secured on a sliding carrier, as the selector bar 502, at intervals corresponding to the space between the depending selector lugs 280 on each of the profile bars 277, which is the same as that between the depending short lugs 343 and between the depending long lugs 344 on each of the fashioning bars 341. Said lift lugs 281 are thus movable with said selector bar 502 to various predetermined operative positions in relation to said profile bars and said fashioning bars where they engage one or another of said different sets of depending selector lugs 280, or lugs 343, 344 according to pattern requirements.

Selector bar 502 is supported at intervals and near its ends in suitable bearings, as the channeled blocks 503, Figures 5, 7 and 8, which are pivotally supported on levers 504, secured at the outer ends of rock shafts journaled in bearings 506. The inner ends of said shafts carry crank arms 507, Figure 8, pivotally connected at 508 to push bar 509. Said push bar 509 is reciprocated endwise against spring resistance by suitable means. This endwise movement of push bar 509 is employed to rock crank arms 507 and thereby levers 504 which raise selector bar 502 and its

lifters 281 while the latter are disposed in any selected lifting position.

Devices for imparting endwise movement i. e. selective positioning to selector bar 502, and thus to lift lugs 281, include a chain 511, Figure 2, having one end connected directly to said selector bar 502 and the other end connected thereto through a spring 512. Said chain 511 is supported between idler sprockets 513 and 514; and is driven by a sprocket 515 secured on a shaft 516, Figures 4 and 5. Controlled rotation in either direction is imparted to shaft 516 by suitable clutch devices interposed between drive shaft 6 and said shaft 516 in accordance with pattern requirements.

Shaft 516 has at its inner end, Figure 5, a gear 517 which meshes with a pinion 518 on a countershaft 519. A bevel gear 520 fixed on an inner end portion of said countershaft 519 meshes with opposed bevel gears 521 and 522 loosely mounted on the continuously rotating main drive shaft 6, Figure 4, said gear 521 being mounted to turn with a ratchet wheel 523, and said gear 522, with a ratchet wheel 524.

A spring biased pawl 525, Figure 6, is pivoted at the outer end of a pawl arm 526 secured to shaft 6 and operates under controlled conditions to rotate shaft 516 in one direction through said countershaft 519. A similar pawl 527, Figure 5, is pivoted at the outer end of a similar pawl arm 528 secured to shaft 6 and operates under other controlled conditions to rotate shaft 516 in the opposite direction through said countershaft.

Means for controlling the extent of rotation of countershaft 519 when actuated by said pawl 525 are shown in part in Figure 6. A plate 529 forming in effect a fixed segment of a pawl controlling or retaining ring provides an inwardly exposed cylindrical surface 530 concentric with shaft 6 and positioned to afford a bearing for the tail portion of said pawl 525 on arm 526 by which the other end portion thereof is held out of engagement with ratchet wheel 523. Said segment defines a gap having its maximum opening extending from shoulder 531 clockwise, Figure 6, to shoulder 532. The extent of said gap is controllably varied by a rotatable ring segment 533 carried at one side of said fixed segment 529 on a spider having a central collar 534 and arms 535, said collar being loose on shaft 6. An actuating arm 536 extends radially from said collar 534 and is operatively connected with control devices, as a control shaft 537, through a link 538 and a crank arm 539 secured on said shaft 537. Said shaft 537 is connected at its outer end portion and actuated by a control link 805 through an arm 806, Figure 1, said link being moved endwise for this purpose by an automatic control device.

The rotatable ring segment 533 provides an inwardly directed cylindrical bearing surface 533a concentric with shaft 6 and of substantially the same angular extent as the gap from shoulder 531 to shoulder 532, and in effect, forms a continuation or extension of the fixed surface 530 in that the tail of pawl 525 normally rides on portions of both of said surfaces during rotation of shaft 6 to hold the nose end of said pawl out of engagement with ratchet 523. However, when during a single rotation of main shaft 6 control shaft 537 is rotated to bring said ring segment 533 into one of its operative positions, as that shown in Figure 6, for example, a gap is left between fixed shoulder 532 and the lower end shoulder 540 of said rotatable ring segment 533. When the tail of pawl 525, moving clockwise, Figure 6, with rotation of pawl arm 526 secured to shaft

6, passes said shoulder 540, ratchet 523 is engaged and turned by the nose of said pawl until further rotation of pawl arm 526 brings said tail portion of pawl 525 against shoulder 532 which disengages the nose of said pawl 525 from driving engagement with ratchet 523.

The parts are so calibrated that each rotation of ratchet 523 to the extent of one tooth thereof, effects one unit of linear movement of the selector bar 502, i. e. the distance from one operative lifting position to the next. Also, the extent of opening of the gap between fixed shoulder 532 and the lower end shoulder 540 of the ring segment 533 determines the extent of operative movement of pawl 525 and hence of ratchet 523. Thus, the various operative lifting positions of said selector bar 502 may be numbered, or otherwise identified, for pattern purposes; and suitable selective control devices are provided to govern the timing, extent, and direction of movement of said selector bar 502. It will be clear that the aforesaid controlled rotation of ratchet 523 will impart equivalent movement to bevel gear 522 and thence through the previously described connections to sprocket 515 in the direction of the dotted arrow, Figure 2. This imparts outward movement (right Figure 2) to selector slide bar 502.

Parts of like function to those above described and as shown in Figure 5, operate in a similar manner to produce controlled rotation of sprocket 515 and therefore linear movement of selector bar 502 in the opposite direction (left Figure 2). For this purpose, a separate control is provided including the control shaft 541 having a crank arm 542. A link 543 connects said arm 542 with a radial arm 544 extending from the hub 545 of a spider which supports a rotatable ring segment 546 in cooperative relation to a fixed segment 547. For controlling adjustment of selector bar 502 in said opposite direction, control shaft 541 is operatively connected at its outer end portion to be rocked by endwise movement of a control link 807 similar to link 805 and actuated by an automatic control device, Figures 1 and 3.

A dial 548, Figures 2 and 5, is secured at the outer end of shaft 516 and carries on its beveled perimeter a series of markings, as ordinals, which identify the various jack lifting positions of bar 502. A fiducial mark or pointer 549 is fixed at a point adjacent the periphery of said dial so that an operator may conveniently ascertain which lifting position of bar 502 is currently effective at any stage of operation.

Said bar 502 will retain any given setting until moved therefrom by operation of the repositioning devices. Thus if bar 502 is at what may be designated as the fifth place it can be repositioned to the third place by a two point reverse movement. The pattern will be so laid out and the profile bars 277 so arranged that the adjustments in any direction will be within the limits of movement of the control mechanism.

My invention, as embodied in the machine above described, provides a relatively simple and rapidly acting mechanism for varying the position of the selector slide bar 502 and thereby determining which of the various profile bars 277 shall be raised or to what extent the fashioning bar 341 shall be lifted. In either case, the effect is to determine which active needles shall produce links-links and which straight knitting in any course where both are required.

The improved arrangement is especially effective when used with the devices, as shown, for automatically determining which needles shall

be active and which idle in any course and with other devices cooperating therewith to produce a variety of pattern effects in knitted products.

The above described mechanisms are also shown and described but not independently claimed in my co-pending application Serial No. 530,761 filed herewith and of which the present application is in effect a division.

I claim:

- 10 1. In a flat links knitting machine wherein main control jacks are movable to one position to cause needles affected thereby to knit links-links and to a different position to cause needles affected thereby to knit straight, the combination of a selector bar having a lug extending therefrom and being slidably mounted endwise for adjusting said lug to and from different operative positions, means for effecting movement of said selector bar toward said jacks, a plurality of
  - 15 transmitting devices operatively interposed between said selector bar and said jacks and each having portions positioned to engage said jacks and other portions positioned to be engaged by said lug to transmit said movement of said bar
  - 20 to said jacks, said other portions being disposed in offset relation to each other and opposite said different operative positions of said lug, and means for adjustably moving said bar endwise to bring said lug thereon into and out of position
  - 25 to engage different ones of said lug engaging portions of the transmitting devices.
- 20 2. In a flat links knitting machine wherein main control jacks are raised from normal inoperative position to different active needle conditioning positions, in one of which the corresponding needles effect links-links knitting and in the other of which the corresponding needles effect straight knitting, the combination of a longitudinally slidable selector bar having a lift lug
  - 35 extending upwardly therefrom, a plurality of lift transmitting plates mounted to be raised from inoperative position toward said jacks and each having a depending lug which extends toward said bar and is disposed opposite a different portion thereof, means for adjusting said bar longitudinally to bring said lift lug into operative position opposite one or another of said depending lugs, and means for raising said selector bar when in said operative position.
  - 40 3. In selector bar actuating mechanism for knitting machines, the combination of a countershaft mounted to rotate in opposite directions, means operatively connecting said countershaft to said bar, a drive shaft, a ratchet operatively connected to said countershaft, a pawl carrying arm fixed on said drive shaft, a fixed pawl guiding member having a segmental cylindrical bearing face concentric with said drive shaft, a rotatably adjustable pawl guiding member having a segmental cylindrical bearing face concentric with said drive shaft and mounted to form an extension of said fixed segmental cylindrical bearing face, a pawl mounted on said pawl arm and having a nose portion biased toward driving engagement with said ratchet and a rear portion positioned to engage said cylindrical bearing faces and retain said nose portion out of operative engagement with said ratchet, and means for actuating said rotatably adjustable pawl guiding member to move one end of its bearing face to and from different spaced relations to an end of the bearing face of said fixed pawl guiding member and thus to form gaps of different angular extent between said ends of said faces.
  - 45 4. In selector bar actuating mechanism for

knitting machines, the combination of a countershaft mounted to rotate in opposite directions, means operatively connecting said countershaft to said bar, a drive shaft, a ratchet operatively connected to said countershaft, a pawl carrying arm fixed on said drive shaft, a pawl retaining ring concentric with said drive shaft and having a fixed segment and a movable segment adjustable in relation thereto, a pawl mounted on said pawl arm and having a nose portion biased toward driving engagement with said ratchet and a rear portion positioned to engage said ring to hold said nose portion out of operative engagement with said ratchet, and means for rotating said movable segment to adjust one end thereof to and from different spaced relations to an end of the fixed segment and thus to form gaps of different angular extent between said ends.

5. In a knitting machine wherein predetermined control jacks are actuated by devices having different control jack affecting characteristics, and wherein said devices are arranged side by side and each has a set of depending lugs, those of each set being offset longitudinally from those of each other set, the combination of a selector bar having spaced lug engaging members, means for adjusting said bar endwise to bring said members into and out of operative relation with one or another of said sets of lugs, and means for actuating said bar, when adjusted, to move in a direction to advance said devices into operating engagement with said control jacks.

6. In a knitting machine provided with needles and jacks arranged and adapted for conditioning said needles for knitting straight or links-links, the combination of a plurality of jack actuating profile bars arranged in parallel relation and movable toward and from said jacks and one of said bars having a different jack positioning effect from another bar, a profile bar actuating device, means operatively arranged between each of said

bars and said actuating device and differentially positioned longitudinally in relation to said several bars to transmit movement of the profile bar actuating device to said profile bars, and means for moving said profile bar/actuating device longitudinally to and from different operative positions to actuate different ones of said profile bars.

7. In a knitting machine provided with needles and jacks movable to one position to condition said needles for straight knitting and to a different position to condition said needles for links-links operation, the combination of a lift plate arranged and adapted to move said jacks to said different positions, a selector bar adjustable longitudinally to one position for straight knitting and to another position for links-links operation, and a fashioning bar arranged and adapted to transmit different conditioning movements to said jacks from said selector bar in said several positions of longitudinal adjustment thereof.

8. In a knitting machine provided with needles and jacks arranged and adapted to be moved to different extents for conditioning said needles to produce different stitch forming effects, the combination of a lift plate operatively related to and movable toward said jacks to effect conditioning movement thereof, a fashioning bar movable toward said lift plate and arranged and adapted to engage and move said lift plate different distances to impart corresponding movement to said jacks, and fashioning bar actuating means movable to engage said bar and adjustable to different positions longitudinally thereof, whereby, when said actuating means actuates said fashioning bar at one position of engagement therewith, said bar moves said lift plate a predetermined extent and when at another position of engagement, moves said lift plate a different extent.
